UNITED STATES PATENT OFFICE

HARVEY GILES, OF BROOKLYN, NEW YORK, ASSIGNOR TO COLLIER ADVERTISING SERVICE, INC., OF NEW YORK, N. Y., A CORPORATION OF DELAWARE

VENDING MACHINE

Application filed May 28, 1931. Serial No. 540,591.

The invention relates to an improvement in vending machines of the type in which an article is delivered when a coin of proper denomination is deposited in the machine and a plunger or handle is manipulated. More particularly the invention is an improvement in the coin controlled article delivery mechanism for such machines.

One object of the invention is to provide in coin-controlled vending machines of the above described type a simplified article delivery mechanism directly controlled by a coin of proper denomination held in a predetermined position to secure a more positive and reliable operation of the machine. Another object of the invention is to provide improved guard means for vending machines of this character positively preventing the insertion of any means whatever into the machine to injure or abstract surreptitiously the articles which are to be vended in return for the deposit in the machine of a proper coin. These objects and other objects the advantages of which will appear as the description proceeds are accomplished in the improved coin controlled vending machine hereinafter fully described and particularly pointed out in the appended claims.

The preferred embodiment of the invention is illustrated in the accompanying drawings in which: Figure 1 is a section taken on the line 1-1 of Fig. 7, and showing in side elevation the left hand side of the operating parts of the machine, the parts being shown in normal position; Fig. 2 is a section taken on the line 2-2 of Fig. 7, and showing in side elevation the coin chute and in section the improved means for holding the coin in predetermined position for engagement by a part of the article delivery mechanism; Fig. 3 is a sectional detail of the resilient coin support and showing the coin engaged by a part of the article delivery mechanism; Fig. 4 is a vertical section through the middle of the machine, the section being taken on substantially the line 4-4 of Fig. 7, the parts being shown in normal or inoperative condition; Fig. 5 is a view similar to Fig. 4, but with the upper and lower parts removed, and showing the

article delivery means in engagement with an article and in the act of pushing it forward; Fig. 6 is a view similar to Fig. 5 but with the article pushed forward into position where it may be obtained by the purchaser, and showing the article delivery means freed from the article; Fig. 7 is a top plan, partly in section, of the operating parts of the vending machine; Fig. 8 is a detail of the right hand end of Fig. 7 and showing the parts in section; Fig. 9 is a view similar to Fig. 8, but with the article moved forward into position to be grasped by the purchaser; Fig. 10 is a horizontal section, taken on the line 10-10 of Fig. 4, and showing the parts in normal, inoperative position; Fig. 11 is a view similar to Fig. 10, but with the plunger moved forward almost to the limit of its outward movement; Fig. 12 is a transverse vertical section, taken on the line 12-12 of Fig. 7; Fig. 13 is a detail of the coin supporting parts for controlling the operation of the plunger, and showing the plunger pulled forward to the limit of its movement when no coin is in the machine; Fig. 14 is a view similar to Fig. 13, but showing the plunger pulled forward to the limit of its outward movement after the insertion of a proper coin in the machine; Fig. 15 is a detail of the coin controlled stop lever for preventing the plunger from being pulled outwardly beyond a certain point when no coin has been deposited in the machine; Fig. 16 is a side elevation of the guard members and showing their positions when a coin has been inserted in the machine and the plunger pulled partly forward; Fig. 17 is a view similar to Fig. 16, but showing the position of the parts when the plunger has been pulled forward to the limit of its outward movement; and Fig. 18 is a detail showing the guard member for closing the coin slot when all the articles have been sold.

The improved coin-controlled article delivery mechanism and the other improved devices of the present invention are adapted for use in connection with the vending of a large number of different kinds of articles, but are more especially adapted for use in vending such relatively large and difficultly

handled articles as chocolate almond bars which are indicated at 20 in the drawings. The almond bars or other similar articles 20 are supported in a horizontal position in a vertical hopper comprising two side walls 21 and 22 which are inturned at their rear and forward edges so as to hold the articles in place. The lowermost article is supported by the ledges 23 which are the inturned lower ends of the supporting walls 24 which support and strengthen the lower ends of the side walls 21 and 22 of the hopper. At their rear ends the ledges 23 are spaced apart to permit the article delivery means to have access to the lowermost article to move it forward, but at their forward ends the ledges are connected by a cross-piece 25. The hopper is supported on the upper edges of two walls 26 and 27 of a frame which also supports the operating parts of the vending machine. For this purpose a transversely arranged plate 29 connected to the two ears 30 which project laterally from the rear ends of the walls 24 rest in the notches 32 formed in the rear upper edges of the frame walls 26 and 27. The forward end of the left hand ledge 23 rests on a pin 33 projecting inwardly from the upper part of the frame wall 27. The frame walls 26 and 27 are held in fixed relation by the cross-rods 34, placed at appropriate points where they will not interfere with the movements of the operating parts, and by the transverse braces 35.

The hopper and the frame for supporting the operating parts of the machine are housed within a vertically arranged casing which is of the usual form and construction and comprises the side walls 36, the rear wall 37, the front wall 38 and the bottom 39, the top of the casing not being shown since it contains no operating parts. In the front wall 38 of the casing is formed an enlargement 40 at which point the articles are delivered through the opening 41 therein to the purchaser. In the upper part of the front wall 38 of the casing is located the slot 42 through which the coin is inserted into the machine, and in the lower part of the front wall 38 of the casing is a slot 43 through which a coin not of proper denomination or a slug is returned to the would-be purchaser. The frame walls 26 and 27 for supporting the operating parts of the machine are held in fixed position in the lower part of the casing by means of the bracket 44 on which the forward lower edges of the side frames 26 and 27 rest and by means of the pins 45 projecting forwardly from the rear wall 37 of the casing and which are engaged by the slotted ears 46 inturned from the rear edges of the frame walls. The frame is prevented against accidental upward displacement by means of a spring pressed latch 48 which engages against the upper surface of the uppermost cross-rod 34.

When the coin 50 is inserted through the slot 42 it passes into an inclined channel 51 constituting the entrance of a coin chute formed between the relatively heavy outer wall or plate 52 supported in upright position by the studs 53 extending inwardly from the upright ears 54 on the frame wall 23, and a relatively thin inner wall 55 the edges of which are inturned and abut against the inner surface of the outer wall 52, to which they are secured at convenient points by the screws 56. At the inner end of the inclined portion or channel 51 of the coin chute is located a magnet 57 for deflecting iron slugs into the return coin chute 58, which constitutes a lower extension of the coin chute proper, and out through the slot 43 where it is held by a spring pressed dog 59 in position to be removed. A leaf spring 60 presses against the tail portion of the dog 59 and holds it in position to catch a coin coming through the slot 43, but permits the dog to be turned so that the coin may be removed. If the coin inserted through the slot 42 is a true coin but is not of proper dimension, it will pass by the magnet 58 and will strike against the coin deflector 62 located in the upper part of the vertical part 63 of the coin chute and be deflected into the return chute 58. If, however, the coin inserted through the slot 42 is of the proper denomination, and therefore of the proper weight, it will tilt the deflector 62 and fall down through the discharge opening 64 in the lower end of the vertical part 63 of the coin chute. The deflector 62 is held in normal position, as shown in Fig. 2, by means of a weighted tail portion 65. A pin 66 by engagement with the edge 67 of the plate 52 prevents the deflector from being moved to a position from which it cannot return. All the parts described above may be of the usual construction and arrangement in machines of this character. The improved parts constituting the present invention will now be described.

When a coin of proper denomination falls through the discharge opening 64 of the coin chute it enters a coin slot 69 cut in the middle part of a horizontal ledge 70 which is inturned from the frame wall 26. The coin 50 is prevented from passing through the slot 69, until after it has performed its function of putting the coin delivery mechanism into condition to deliver an article, by means of a guard plate or coin support 72 adjustably secured to an arm 73 pivoted at 74 on the rear end of the ledge or plate 70. The arm 73 is pressed inwardly to hold the guard member 72 over the rear end of the slot 69 by means of the two leaf springs 75 secured to the inner surface of the frame wall 26. The engagement of the inner edge of the arm 73 with a notched plate 71 secured to the ledge 70 and forming part of the coin slot 69 determines the coin-engaging position of

the adjustable plate 72. The plate 72 engages the rear edge of the coin the forward edge of which engages the forward edge 69a of the slot 69. The inner coin engaging edge 6 of the plate 72 is beveled, as at 76, so that when the coin has performed its function of aiding in the delivery of the article and it is to be permitted to drop down through the slot 69 into the receptacle 77, the swinging of 10 the arm 73 outwardly will instantly disengage the surface 76 from the coin and permit it to fall through the slot 69.

The article delivery mechanism comprises, in addition to the parts for holding the coin 15 in predetermined vertical position, a reciprocatory plunger 79 having on its outer or forward end a handle 80. The plunger 79 is substantially as long as the lower part of the machine casing is deep and is supported 20 on a horizontally and longitudinally arranged bracket 81 which is slotted at 84 throughout its length to accommodate the guiding screw 82 which passes loosely through the slot and enters the lower side 25 of the rear end of the plunger. The plunger is normally held in its retracted or inoperative position by means of a contraction spring 30 one end of which is fastened to the plunger and the other end of which is fixed to a pin 35 projecting inwardly from the frame wall 27. The spring 35 passes over a guide wheel 37 journaled on a stud 38 projecting inwardly from the frame wall 27.

The means for engaging the lowermost 40 article 90 of the stack of articles in the hopper and advancing it to position from which it can be removed from the machine when a coin of proper denomination has been inserted in the machine and the plunger drawn 45 outwardly comprises a plate 92 having at its forward end down turned ears 93 by which it is pivotally connected with the boss 94 extending upwardly from about the middle of the upper surface of the plunger. The plate 92 extends rearwardly beyond the article containing 50 hopper and the rear end 95 of the plate 92 is upturned for the purpose of engaging the rear end of the lowermost article in the hopper in pushing it forwardly. In 55 the normal or inoperative condition of the operating parts of the machine the rear end of the plate 92 rests against the upper surface of the rear end of the plunger 79, as shown in Fig. 4. When it is attempted to pull the 60 plunger 79 outwardly without first depositing a coin of proper denomination in the machine, the plunger is prevented from moving beyond a certain point by means of a latch lever 97 pivoted at 98 on an inward extension of the ledge 70. The pointed rear end 99 of the lever 97 constitutes a stop dog which is normally pressed against the side of the rear end of the plunger 79 by means of a spring 100.

As the plunger is drawn forward, when no 65 coin is in the machine, the spring 100 draws

the pointed end 99 of the lever 97 into the notch 101 formed in the rear end of the plunger and thereby prevents the plunger from being drawn farther outwardly. But when a coin of proper denomination has been 70 deposited in the machine and it is held in vertical position in the slot 69 by the resilient guard plate 76 and the plunger is drawn outwardly, the end 99 of the lever 97 is prevented from being drawn into the notch 101 by the 75 spring 100. As the notch 101 moves opposite the end 99 of the lever 97, and the spring 100 attempts to draw the lever end 99 into the notch, the forward end 103 of the lever 97 encounters the inner side of the lower part 80 of the coin projecting through the slot 69. See Fig. 3 which shows the position in which the coin 50 is held in the slot 69 by the guard plate 76. The plunger is thus enabled to complete its full forward movement. To prevent the plunger from returning to its rearward normal position before completing its full forward movement, the lower edge of 85 the plunger is provided with the usual rack 104 located in the slot 84 and adapted to be 90 engaged by the dog 109 held in normal position by a spring 110, the lower end of which is connected to a pin 107 fixed in a bracket 95 108 extending downwardly from the support 81.

While the coin is held in its vertical position in the coin slot 69 by the guard member 76 while the plunger is being drawn outwardly, an arm 105, connected to the plate 92 by the bar 106, but lying on a lower plane than the plate 92 and extending rearwardly parallel with the plate 92, rides up over the top edge of the coin held in the coin slot and thereby raises the plate 92 so as to bring the rear upturned edge 95 thereof in line with the rear end of the lowermost article 90 in the hopper. The middle section of the lower edge of the plate 92 is cut away to permit the upturned rear end 95 of the plate 92 to be positioned to the rear of the lowermost article 90 in the hopper.

When the article 90 has been moved forward into position where it can be removed from the machine by the purchaser, a cam lug 107 on the side of the rear end of the plunger encounters the inturned forward end 108 of the arm 73, thereby forcing the arm 73 outwardly and disengaging the plate 72 from the coin. The coin may now fall through the slot 69 down into the coin box 120 77. A vertically arranged deflector member 109 aids in directing the coin into the coin box. In order that the slight pressure exerted upon the lower part of the coin by the forward end 103 of the lever 97 by the light 125 spring 100 may not interfere with the dropping of the coin through the slot 69, a release lever 111 pivoted at 112 on the forward end of the bracket plate or ledge 70 has its forward end in the path of a cam lug 113 to 130

be engaged and moved thereby before the lug 107 engages the inturned end 108 of the arm 73. The rearwardly extending arm 114 of the lever 111 is articulated by a pin-and-slot 5 connection 115 with the forward end of the lever 97, so that when the forward end of the lever 111 is moved outwardly by the lug 113, the inner end of the arm 114 is moved inwardly and thereby disengages the end 103 10 of the lever 97 from the coin. When the coin drops through the slot 69, the arm 105 and the plate 92 descend to normal position, as shown in Fig. 6.

The article is not pushed all the way out of 15 the machine by the article delivery means 92 on the plunger, but the forward end of the article enters a box-like structure or device 117 located under the hood 40 and to the rear of the opening 41 therein. The device 20 or structure 117 has a central horizontal opening 118 in alignment with the lowermost article 90 in the hopper, so that the forward end of the article 90 may enter the opening 118. The full forward movement 25 of the plunger leaves the article with its forward end substantially flush with the forward edge of the device 117, as shown in Figs. 6 and 9. Before the article reaches this position, the cam lugs 113 and 107 will 30 have engaged the lever arms 111 and 108 and have permitted the coin to descend through the slot 69 and the arm 105 to descend and thereby disengage the rear end of the plate 92 from the article. To permit of the removal 35 of the article from the machine, the front face of the structure 117 is made concaved as clearly appears in the drawings to accommodate the fingers of the purchaser.

While the machine is in normal condition, 40 access to the interior of the machine through the opening 118 is prevented by the inner guard member 120, and after the plunger has been pulled forward a certain amount and until it reaches its rearmost position, the 45 outer face of the device 117 is closed by an outer guard member 121. Thus all surreptitious access to the articles to be vended is effectually prevented, both during the normal inoperative condition of the machine and 50 during the act of delivering an article. The inner guard member 120 is a transversely arranged plate having a strengthening upper lip 122. The plate 120 is carried by the forward ends of two arms 123 and 124 pivoted 55 at their rear ends on the pins 125. During the normal condition of the machine the plate 120 is held lowered to the rear of the opening 118 in the device 117 by means of a 60 dog 126 pivoted at 127 on a lug 128 extending upwardly from the frame plate 27. The lower end of the dog 126 is notched to engage a pin 129 extending outwardly from the arm 124. The dog 126 is held normally in engagement with the pin 129 to keep the plate 65 120 in fixed position at the rear of the open-

ing 118 by means of a tension spring 130. The plate 120 is lifted on the outward movement of the plunger after a coin of proper dimension has been inserted in the machine by means of a cam lug 131 extending outwardly from a vertically arranged plate 132 adjustably carried by the pins 133 and 134 extending laterally from the rear end of the plunger 79 and projecting through a horizontal slot in the plate 27. The forward edge of the cam lug 131 encounters the cam surface 135 to raise the guard plate 120, the dog 126 is freed from the pin 129 by a block 136, mounted on the lug 131, encountering the lower end 137 of the dog. 75 80

The outer guard member 121 is normally held raised above the device 117, as best shown in Fig. 1, since the inner end of the opening 118 is closed by the inner guard member 120. The outer guard member 121 is supported on the forward ends of the two arms 138, 139 pivoted at their rear ends on the pins 125. The arm 139 is provided with a camslot 140 which receives the outwardly extending end 149 of the pin 133. When the parts of the machine are in normal position, the rear lower end of the cam slot 140 is engaged by the pin 133 and thereby holds the forward end of the arms 138 and 139 raised and with them the outer guard member 121. A contraction spring 152 assists in holding the forward ends of the arms 138 and 139 raised. On the outward movement of the plunger after a coin has been inserted in the machine, the pin 149 encounters the inclined surface 141 of the slot 140 and thereby lowers the outer guard member 121 and places it in front of the device 117 in which position it continues until the plunger returns to its normal retracted position. The lifting of the inner guard member 120 from behind the opening 118 and the lowering of the outer guard member 121 in front of the opening 118 are properly timed with respect to each other and to the moving of the forward end of the article 90 into the opening 118, the guard member 120 being raised just before the article reaches it and the guard member 121 being lowered before or at the time the guard member 120 is raised. It is thus seen that the guard member 121 remains in front of the opening 118 while the forward end of the article enters it and that access to the article to remove it from the machine cannot be had until after the plunger is released and is permitted to return to normal retracted position. 90 95 100 105 110 115 120 125 130

The operation of the machine is briefly as follows: Assuming that a coin of proper dimension has been inserted through the slot 42, it first passes down the inclined portion 51 of the coin chute, then into the vertical portion 63 thereof where it encounters the deflector 62. Being of the proper size and weight, the coin turns the deflector on its 125 130

pivot point and drops down through the discharge opening 64 and into the entrance of the coin slot 69 where it is held in vertical position between the forward edge 69a of the 5 coin slot and the beveled edge 76 of the guard plate 72 carried by the spring pressed arm 73. After depositing the coin in the machine, the purchaser pulls the plunger 79 outwardly by means of its handle portion 80. As the 10 plunger moves outwardly, its notched rear end comes opposite the pointed lever end 99, but the lever end 99 is prevented from entering the notch 101 in the plunger by the engagement of the forward end 103 of the lever 15 97 with the side of the coin held in the slot 69 by the guard member 72. The plunger is thus free to be pulled all the way out. When the notched rear end of the plunger passes by the pointed end 99 of the lever 97, the arm 105 of the article delivery plate 92 encounters and 20 rides up on the coin held in the slot 69, thereby raising the plate 92 and placing the upturned rear end 95 thereof behind the lowermost article 90 in the hopper. The continued 25 forward movement of the plunger pushes the forward end of the article into the opening 118 of the device 117 until the forward end of the article is substantially flush with the forward edge of the device, at about which point 30 the lever arms 108 and 111 are engaged by the cam lugs 107 and 113 on the plunger to free the coin and permit it to drop down through the slot 69 into the coin box 77. During the outward movement of the plunger 35 and before the forward end of the article reaches the inner end of the opening 118, the forward edge of the cam ledge 131 encounters the cam surface 135 and raises the guard member 120. Just before or at the time the 40 guard member 120 is raised, the engagement of the cam surface 141 of the slot 140 by means of the pin 149 causes the guard member 121 to be lowered in front of the opening 118. The guard members continue in this 45 relative position until the plunger has been pulled all the way out and is again moved into retracted position, the inner guard member 120 being released first and permitted to drop down upon the upper surface of the article 50 and then the guard member 121 being raised to permit the purchaser to remove the article. As the article is removed, the inner guard member 120 drops down behind the opening 118 and effectually seals it, the pin 55 129 being lowered to permit the notched lower end 137 of the dog 126 to swing into engagement therewith to hold the inner guard member in lowered position until the next operation of the machine.

60 The machine thus continues to operate until the articles have been delivered to a predetermined extent. When the articles in the hopper have been lowered to the predetermined level by the delivery of the successive 65 bottom articles from the hopper, the pin 143

projecting forwardly from the weight 144 resting on the topmost article 145 in the hopper, encounters the inturned lower end 146 of a pivoted guard member 147 and moves the upper end 148 thereof over the coin slot 42, 70 thereby preventing further insertion of coins into the machine. The pivoted guard member 147 is in an unbalanced condition, and when the arm 146 thereof is released, the member 147 moves to the position shown in 75 Fig. 18, exposing the slot 42. The stop pins 150 by engagement with the opposite sides of the plate 52 limit the movement of the guard member.

Having thus described the invention, what I claim as new is:—

1. In a machine of the character described including a reciprocable plunger, a lever for cooperating with the plunger to prevent it from being moved beyond a certain point when no coin has been deposited in the machine, resilient means for holding a coin deposited in the machine in position to be engaged by the lever to prevent the latter from cooperating with the plunger whereby the plunger may be moved beyond said certain point, a cam lug on the plunger for disengaging the lever from the coin and a second cam lug on the plunger for disengaging the resilient holding means from the coin. 90
2. In a vending machine of the character described including a hopper for containing articles to be vended, article delivery means normally out of article engaging position, a manually operable plunger on which the article delivery means is movably mounted, means for cooperating with the plunger to prevent the plunger from moving beyond a certain point when no coin has been deposited in the machine, and means for resiliently holding a coin, said coin preventing the plunger engaging means from cooperating with the plunger whereby the plunger is free to be moved, said coin also serving when the plunger is moved to engage and move the article delivery means into article engaging position. 100
3. In a vending machine of the character described including a vertically arranged article containing hopper having an open lower and exposing the lowermost article in position to be delivered from the machine, a reciprocable plunger having a notch, a spring pressed lever for entering the notch to prevent the plunger from being moved beyond a certain point when no coin has been inserted in the machine, means for holding a coin inserted in the machine in position to be engaged by the lever to prevent it from entering the notch, whereby the plunger is free to be moved, and an article delivery member normally out of article engaging position adapted to engage the coin and to be thereby moved into position to engage and deliver the lowermost article from the hopper. 110
4. In a vending machine of the character 120

described including a vertically arranged article containing hopper open at its lower end to expose an article to be delivered from the machine, a reciprocable plunger arranged to move axially of the articles in the hopper, an article delivery member pivotally mounted on the plunger and extending rearwardly thereof, said member having an upturned rear end adapted to engage behind the lowermost article in the hopper, but being normally out of article engaging position, means for preventing the plunger from moving beyond a certain point when no coin has been inserted in

the machine, said means being controlled by a coin of proper denomination inserted in the machine for permitting the plunger to be moved, means for holding the coin in the path of the article delivery member whereby the upturned rear end of said member is moved into article engaging position to move the lowermost article in the hopper forwardly into position to be removed from the machine, and means controlled by the plunger for releasing the coin to permit the article delivery member to move into inoperative position.

HARVEY GILES.
